SELF-BALANCING BARRIER GATE

Benjamin Cooper and Murray J. Charet, Brooklyn, N. Y.,
said Charet assignor to said Cooper

Application November 19, 1955, Serial No. 546,061

3 Claims. (Cl. 39—43)

This invention relates generally to barrier gates and 15 more particularly to a novel self balancing barrier gate.

Barrier gates per se are well known in their public use as readily removable barriers which prevent access to railroad crossings or toll facilities, or the like. The particular barrier gate hereinafter described is particularly adapted though not limited to, use with toll facilities. It is conventional to use a barrier gate at toll facilities when the vehicular lane is closed to traffic. Heretofore, the common pivotal type barrier gate which swings horizontally has been utilized. This type requires the manual movement throughout the entire swing of the gate. The present invention provides a novel self balancing structure which may be readily moved in a vertical arcuate path for a portion of the arc of travel and which will continue automatically till it is arrested at the limit of movement. The present gate, briefly may be described, as the type which is pivotal from a horizontal position to a substantially vertical position. In the former position, the vehicular lane is blocked by the arm of the gate and traffic may not pass therethrough. When raised to the substantially vertical position, the vehicular lane is unobstructed and vehicles may proceed as required. Heretofore, self balancing gate have relied solely upon counterweights to facilitate the opening and closing thereof. Such counterweights introduce severe shock upon the arresting of movement thereof. The present invention employs a novel toggle-type mechanism incorporated with shock absorbing means to permit the gate arm to continue movement in a free, unrestricted manner while preventing any shock at the end of the path of travel.

Accordingly, one of the principal objects of the invention resides in the provision of a novel barrier gate balancing mechanism having means to both assist and retard the movement of the gate arm during respectively different portions of the path of travel of said gate arm.

Another object of the invention resides in the provision of a barrier gate having means to adjust the retarding and assisting means.

A further object is to provide a novel toggle-type mechanism for assuring against accidental movement of the barrier gate.

Other ancillary objects will be, in part, hereinafter pointed out and will be, in part, hereinafter apparent.

In the drawings:

Figure 1 is a perspective view of the barrier gate illustrating the gate arm in horizontal position.

Figure 2 is a side elevation of the gate mechanism with the side covers removed to more fully illustrate the component parts thereof.

Figure 3 is a plan view of the gate mechanism with portions of the mechanism omitted to clarify the understanding of the remaining portions.

Figure 4 is an end view with the rear cover removed, showing the disposition of the various elements of the mechanism.

Referring to the drawings in detail, 10 generally design-

2

nates the barrier gate having a supporting structure 12, comprising a top wall 14, a pair of parallel side walls 16, a front wall 18 and a rear wall 20. The top wall 14 abuts against an angular wall 22 which in turn engages the front wall 18. Provided in the top wall 14, angular wall 22 and front wall 18 is a slot 24 for a purpose hereinafter appearing. As shown in Figure 1, a stub arm 26 extends outwardly from said slot and is provided with a socket 28 therein. The barrier gate arm 30 is adapted to be inserted within the socket 28 and secured therein by means of bolts 32 or the like. Barrier gate arm 30 has affixed to the free end thereof indicia bearing member 34 for a purpose hereinafter apparent.

The supporting structure for gate arm 30 comprises a frame work 36 generally consisting of pairs of angular members 38, 40, 42, 44 and 46. These angular members are provided in pairs in opposed relation and secured therebetween are further members which co-operate to form a substantial rigid structure. Diagonal member 50 is secured by welding or the like between each of the base members 40 and the respective vertical members 42. A cross plate 52 is centrally affixed to and disposed between the diagonal members 50 for a purpose hereinafter appearing. As shown in Figure 4, there is provided a pair of hinge pins 54 which are disposed in aligned relation and supported by the respective side plates 16. Hinge pins 54 provide the pivotal point around which the gate arm 26 rotates.

Means are provided to mount the stub arm 26 on the hinge pins 54 and directed toward this end there is provided a U-shaped member 56 which has in the respective arm portions, coaligned apertures 58 which are adapted to receive the hinge pins 54 therein. Stub arm 26 is affixed to the base section of the U-shaped member 56 by welding or the like and arcuately pivots therewith about the pivot pins 54. Also secured to the base portion of U-shaped member 56 are a pair of spaced shackles 60 which are adapted to secure the ends of a pair of coil springs 62 thereon. Similarly, the cross plate 52 is provided with a pair of shackles 60 which are adapted to secure the opposite ends of the respective coil springs 62 thereon. As shown in Figure 2, the upper shackles 60 are positioned forward and below the axial center of the pivot pins 54. Thus, in effect, springs 62 provide an over-the-center acting toggle.

Accordingly, springs 62 will retain the arm 26 and co-extending arm 30 in their respective arrested positions and only when the gate arm is moved more than forty-five degrees will the gate arm seek its secondary position.

Thus, it will be obvious that manual movement of the gate arm slightly more than forty-five degrees will result in the toggle springs 62 motivating the arm the remainder of the distance of travel. In moving gate arm 30 from one position to the other, springs 62 will expand until they pass through the axis of pivot pins 58. After passing through said axis, the expanded springs 62 contract and assist gate arm 30 in movement. This assistance is desirable, however, for the shock of the stub arm 26 against the prepositioned stop 70 would be damaging to the gate arm per se and to the pins 54. The present arresting shock means are provided to arrest the pivotal movement of the stub arm 26 prior to the engagement thereof with the stop 70. Directed toward this end is a shock absorber 72 of conventional structure wherein two telescoping sleeves 74 and 76 respectively which co-operate to retard opposite axial sliding movement thereof. The shock absorber 72 is conventional and well known to any one skilled in the art. It may be briefly stated that the shock absorber 72 will compress as the gate arm is raised or lowered to a minimum length as the gate passes through dead center or forty-five de-

grees. Upon the continued movement, the shock absorber is expanded and it is during this expansion process that the shock absorbing elements therein co-act to retard continued movement of the gate arm. The shock absorber 72 is secured at one end to a shackle 78 adjustably attached to the plate 52 and is pivotally secured at its opposite end to an extension 80 which extends rearwardly from the base of U-shaped member 56 in a direction coaxial but opposite from the extending direction of the gate arm. A shackle 82 pivotally connects the sleeve 74 of shock absorber 72 with the extension 80. As shown in Figure 2, the member 26 abuts against stop 70 when said gate is raised or in its uppermost vertical position such as shown in dotted line. The gate arm 26, as shown in full lines in its lowermost or horizontal position abuts against a resiliently covered stop 84.

In operation, the gate arm 26-30 is raised manually until springs 62 pass dead center or in alignment with an axis drawn through said springs and along the center of said gate arm. During this preliminary movement, the shock absorber sleeve 74-76 telescopes inwardly and offer little resistance to the movement of the gate arm. Upon passing through dead center, the springs 62 then motivate the continued movement of the arm 30 with a toggle action until the gate is arrested by the stop 70. Just prior to the gate arm reaching its end of travel, the expansion of the telescoping members of shock absorber 72 is most effective and the movement of the gate is in effect slowed down by the shock absorber action which tends to cancel the motivating power of the springs 62. Such shock absorber action is conventional and well known to those skilled in the art.

Thus, it is apparent that there has been provided a device in which the several objects of the invention

are achieved and which is well adapted to meet the conditions of practical use.

While there has been shown and described a single embodiment of the invention, it is to be understood that modifications and changes might be made without departing from the scope of the present invention, except as limited by the following claims:

The invention claimed is:

1. A barrier gate comprising a gate arm, support means having a pivot means operatively connected to a rear portion of said arm, a pair of stop means on said support means having engagement with said arm at the opposite limits of its swinging movement, spring means and retarding means operatively connected to said arm at points spaced from and on opposite sides of said pivot means, respectively, and also connected to said support means intermediate the opposite limits of the swinging movement of said arm.

2. The combination of claim 1, said spring means comprising a tension spring connected at one end to said arm forwardly of said pivot means, and said retarding means being connected at one end to said arm rearwardly of said pivot means and comprising means to retard elongation of said retarding means, and said spring means and retarding means being connected at their other ends rearwardly of said pivot means.

3. The combination of claim 2, the connection at said other end of said spring means and retarding means being located on a common axis.
